UNITED STATES PATENT OFFICE.

JAMES E. GILLESPIE, OF WARWICK, NEW YORK, ASSIGNOR TO THE FABRIC FIRE HOSE COMPANY, OF SAME PLACE.

MULTIPLE-FABRIC HOSE.

SPECIFICATION forming part of Letters Patent No. 268,366, dated November 28, 1882.

Application filed July 5, 1882. (No model.)

To all whom it may concern:

Be it known that I, JAMES E. GILLESPIE, of Warwick, in the county of Orange and State of New York, have invented a new and useful Improvement in Multiple-Fabric Hose, of which the following is a specification, reference being had to the accompanying drawings.

In two-ply woven or fabric hose, as ordinarily constructed, the two plies are entirely distinct from each other, each having its own warp and its own weft, and the wefts of both plies run through their respective warps in the same spiral direction. When the hose thus constructed is subjected internally to hydraulic pressure it is liable to twist and squirm in a very objectionable manner.

The principal object of this invention is to obtain two-ply hose that is free from this liability to twist and squirm; and to this end the 20 said invention consists in a two-ply hose the wefts of the two plies of which run in opposite spiral directions through the warps. The effect of this arrangement of the two wefts is that the tendency of each weft to produce a 25 twist of the hose in one direction is counteracted by the tendency of the other weft to produce a twist in the opposite direction, and the twisting of the hose is prevented.

In carrying out my invention the warp and 30 weft of each of two plies of the hose may be woven together independently of the warp and weft of the other ply; but I prefer to weave the two plies together by causing a certain number of the warps to be woven into and incorporated with both plies.

Figure 1 is a transverse section of a piece 35 of two-ply hose constructed according to my invention, and having certain of the warp-threads woven into both plies. Fig. 2 is a section taken through one side of this hose 40 in a longitudinal direction, or parallel with the warp. Fig. 3 is a face view of a portion of the hose projected on a plane, and representing it with a portion of the outer ply removed to show the threads of the inner ply.

i i represent the warp-threads of the inner 45 ply. *o o* are the warp-threads of the outer ply. *w w* are the weft-threads of the outer ply, and *w' w'* are the weft-threads of the inner ply. *l l* are the locking-threads of the warp, passing 50 through both plies and securing the two together. (Represented in Figs. 2 and 3, and shaded with diagonal lines.)

It will be seen by referring to Fig. 3 that the threads *w w* of the outer weft and those 55 of the inner weft run in opposite spiral directions.

My improved hose, made without incorporating any of the warp-threads into both plies, may be woven in a hand-loom constructed and 60 organized like the hand-looms commonly used for weaving two-ply hose, except that the two shuttles, instead of being both put into and passed around in the same direction, will be put thereinto and passed around the warp 65 in opposite directions; or such hose may be woven in a circular loom with two shuttles working in different planes, the said shuttles running one in one direction and the other in the opposite direction. When the two plies 70 are to be woven together, as represented in the drawings, the harness is so organized and operated that some of the warp-threads are so worked as to be incorporated into both plies. This method of working the warp and the necessary method of organizing the harness will be intelligible to the expert weaver without 75 explanation; but I will here state that it is explained in my application for patent for improvements in circular looms, No. 69,199, filed August 12, 1882, parts of which improvements are specially adapted for weaving hose composed of two or more plies the wefts of which run in opposite directions through the 80 warps, and in which a certain number of the 85 warps are woven into and incorporated with two or more plies of the warp.

The invention may be applicable to fabric hose having any even number of plies more than two, the contiguous plies always having 90 their wefts running in opposite directions.

What I claim as my invention is—

1. A two-ply or multiple woven or fabric hose in which the wefts of contiguous plies run in opposite spiral directions, substantially 95 as herein described.

2. A two-ply or multiple woven hose in which the wefts of the contiguous plies run in opposite directions, and certain of the warp-threads are incorporated into two plies, substantially as herein described. 100

JAMES E. GILLESPIE.
